UNITED STATES PATENT OFFICE

2,631,296

SANITARY TOILET BOWL APPLIANCE

Otto Klabunde, Chicago, Ill.

Application October 17, 1949, Serial No. 121,823

5 Claims. (Cl. 4-1)

1

The present invention relates to toilet devices and has for its main object the provision of a device utilizing current of water for washing parts of the body in substitution of the commonly used toilet paper. The device is primarily intended for use in cases of various rectal afflictions in which common toilet paper is too irritating.

Another object of the present invention is the provision of a rotatable wheel along which a current of water is thrown when the wheel is shifted toward a part of the body for cleansing the same, and which wheel may be adjustable vertically and laterally to adapt the same to a proper position of the user's body.

With the above general objects in view and others that will appear as the invention is better understood, the same consists in the novel construction, combination and arrangement of parts hereinafter more fully described, illustrated in the accompanying drawing and pointed out in the appended claims.

In the drawings forming a part of this application, and in which like designating characters refer to corresponding parts throughout the several views:

Fig. 1 is a side elevational view of the present device connected with a toilet bowl;

Fig. 2 is an enlarged side elevational view of the device;

Fig. 3 is a cross-sectional view on line 3-3 of Fig. 2;

Fig. 4 is a cross-sectional view on a horizontal plane through the device, the view having been taken on line 4-4 of Fig. 2;

Fig. 5 is a cross-sectional view on a vertical plane through the device, the view having been taken on line 5-5 of Fig. 4; and

Fig. 6 is a front elevational view of a mounting means permitting the device to angularly shift upon vertical and horizontal planes in order to adapt the device to assume a proper position with relation to the position of the user's body.

Referring in detail to the present drawings there is shown a toilet bowl 10, to the rear portion of which a pair of supporting bars 11 is rigidly connected by means of bolt 12. Each of said bars 11 at its rear end supports a pair of spaced arms 13 upwardly projecting from said bars 11 and pivoted thereto as at 14. The upper ends of each pair of said arms 13 are pivoted to a side flange 15 rigidly formed with and downwardly depending from platform 16. Thus, four of said arms are in a pivotal relation with said bars 11 at their lower ends and with said platform 16 at their upper ends.

2

Platform 16 supports pin 17, which by its lower end is riveted to said platform as at 18. Oblong block 19 has a central bore, through which said pin 17 is extended for permitting said block 19 to angularly shift thereabout in either direction. The upper end of said pin 17 extends above the upper face of said block 19.

Extending from the upper face of block 19 is a pair of pins 20, one adjacent each end of said block 19. Said pins 17 and 20 are in alignment longitudinally of block 19, and each is provided with a transverse slot for reception therewithin of leaf spring 21. Since pin 17 is in a rigid, stationary position with relation to platform 16 any turning of block 19 upon said pin 17, in either direction, will be effected against the tension of spring 21, the latter urging said block 19 to its normal, neutral position shown in Fig. 4, for the purposes hereinafter specified.

The device further includes plate 22, provided at its lower edge with central recess 23. Integrally formed with and downwardly extending from the lower edge of said plate 22 is a pair of hinge arms 24, one adjacent each edge of said plate 22. Said hinge arms 24 extend forwardly of the exposed face of said plate 22 and are in a perpendicular relation therewith. Each of said hinge arms 24 is mounted upon pintle 25 frictionally receivable within bore 26 made longitudinally of said block 19 and in the path of pin 17. Each of said pintles 25 is provided with recessed head 27. Looped end of leaf spring 28 encompasses head 27 and is anchored within the recess of said head 27 for maintaining said spring 28 in position. The upper end of said spring 28 extends upwardly from head 27 and bears against the adjacent face of said plate 22, for normally maintaining said plate 22 in a perpendicular relation with platform 16. Extending into said block 19 in transverse relation with bore 26 is a pair of screws 29, which bear against pintles 25 for maintaining them in a fixed rotatably adjusted position. Said pintles 25 and heads 27 are capable of rotatable adjustment on loosening screws 29 for the purpose of shifting the upper ends of springs 28 to or away from plate 22 and thereby of regulating the tension of said springs 28 against plate 22.

Affixed in any suitable manner to the opposite face of said plate 22 is closure plate 30, which constitutes a closure for the adjacent open face of turbine casing 31, with which casing said plate 30 is in any suitable manner rigidly connected for maintaining said casing 31 closed. Positioned within said casing 31 is a bevelled turbine wheel 32, which is of a bevelled formation reposing

within a correspondingly formed cavity 33 in said casing 31.

Formed upon the rim of said turbine wheel 32 is a plurality of vanes 34. Adjacent the upper end of said casing 31, and at one side thereof, flexible tube 35 is connected to said casing 31, the latter being provided with bore 36, communicating with said tube 35 and with cavity 33 adjacent the upper portion of turbine wheel 32. When water is forced through said tube 35, the same plays against vanes 34 for the purpose of rotating wheel 32.

The outer face of said casing 31 is provided with boss 37, which constitutes a bearing for one end of shaft 38, upon which turbine wheel 32 is journaled for rotary movement. The opposite end of said shaft 38 is set within bearing 39, which is accommodated within cavity 40 made in turbine wheel 32. Said bearing 39 also extends through bore 41 made in closure plate 30. The opposite end of shaft 38 has gear 42 keyed thereto, which meshes with gear 43. Said gears 42 and 43 are accommodated within the cavity made adjacent the inner face plate 22.

The device further includes a pair of spaced arms 44, which normally are in a horizontal position, and which are in a perpendicular relation to plate 22. One of said arms 44 has a reduced boss 45 which is frictionally receivable within a bore made in said plate 22. The opposite arm 44 receives bearing 46, frictionally receivable within said latter arm 44. Said bearing 46 has a reduced stud 47, extending beyond the end of said arm 44, and is frictionally receivable within a bore made in said plate 22. Extended through said bearing 46 and stud 47 is shaft 48 which is rigidly affixed by one of its ends to said gear 43, said latter arm 44 being provided with bore 49, within which said shaft 48 is accommodated.

Frictionally connecting with the outer ends of said arms 44 is a pair of wheel supporting members 50, one of which has a cavity 51 into which the opposite end of said shaft 48 is extended. There, said shaft 48 has gear 52 keyed thereto. Collar 53 frictionally receivable upon said end of said shaft 48 maintains said gear 52 in position, and in contacting relation with the adjacent end of said last mentioned arm 44.

Receivable within said members 50 is wheel 54, which, upon one of its faces carries an annular gear 55 which is in mesh with gear 52. Extended through said members 50 is screw bolt 56, upon which lining 57 and an encompassing hub sleeve 58 are set. Said hub sleeve 58 is in a rigid engagement with wheel 54. Said lining 57, hub sleeve 58 and wheel 54 are journaled upon said screw bolt 56 for rotary movement thereupon. A pair of races 59, rigidly affixed to the inner faces of said members 50, with said screw bolt 56 passed therethrough, support ball bearings 60 in contact with the ends of said hub sleeve 58 for facilitating free rotary movement of said wheel 54 upon said screw bolt 56.

The rim of said wheel 54 is enlarged and is in an overlapping relation with the ends of said members 50, as is clearly seen in Fig. 4. Said rim is also bevelled for providing a convenient body contacting surface.

Plate 30 is provided with exhaust vent 61 made at a point farthest removed from said tube 35 and bore 36. Said exhaust vent 61 is in communication with cavity 33 and along the path of vanes 34. At least one of said vanes 34 is capable of being accommodated intermediately of the inner end of bore 36 and exhaust vent 61. When water

is forced through bore 36 from tube 35 against one nearest vane 34, the same is propelled towards the point of said cavity 33 disposed oppositely of said exhaust vent 61. Water carried by the pockets defined by said vanes 34 is exhausted through said exhaust vent 61.

Connecting with said exhaust vent 61 is tube 62, having elbow 63, which directs the lower end of said tube 62 into a central relative position with relation to said arms 44, as is seen in Fig. 4. The upper peripheral portion of said tube 62, adjacent its lower end, and in the proximity of the rim of wheel 54 is cut away, and the remaining portion of said tube 62 is laterally spread out to provide a gutter 64, best shown in Fig. 3, in a spaced relation with the rim of said wheel 54, for the purpose of directing the exhausted water through tube 62 into a comparatively thin stream flowing against the periphery of said rim. Thus, the water flowing through said gutter 64 against the rim of said wheel 54 cleans it by removing any adhering waste particles. For further cleaning the rim of said wheel 54 a roll of cotton 65 may be positioned upon the upper peripheral portion of tube 62, adjacent wheel 54, held in position by collar 66, which is carried by said tube 62. The adjacent end of said cotton roll 65 remains in contact with the rim of wheel 54 for further removing any adhering particles thereto.

From the hereinabove description it will be seen that when turbine wheel 32 rotates, the same will impart rotary movement to shaft 38, which in turn will cause rotation of gear 43, imparted thereto through gear 42. Gear 43 will impart rotation to shaft 48, which in turn will rotate gear 52 for imparting rotary movement to gear 55. The latter gear, being rigidly affixed to wheel 54 will cause the rotation of said wheel 54 upon screw bolt 56. The rotation of wheel 54 will be in the direction indicated by arrow in Fig. 2. Thus, the stream of water exhausting itself through gutter 64 and against wheel 54 will do so after the preceding portions of said wheel have contacted the user's body, for removing adhering particles from said wheel 54 and for cleaning the same as was hereinabove stated. Thus, the portions of said wheel 54, having passed gutter 64 and cotton roll 65 have been cleansed preparatory to continuously succeeding contact with the user's body.

Connected with one of said arms 13, and laterally extending along toilet bowl 10 is handle 67, which, when manually grasped and depressed, constitutes the means whereby the upper portion of said arms 13, platform 16 and the entire device upon platform 16 is capable of bodily shifting towards and above bowl 10. To retract said arms 13 and the present device to their inoperative position, shown in Fig. 1, when handle 67 has been released, leaf spring 68 is affixed to one of said bars 11. The opposite end of said leaf spring 68 bears against one of said arms 13 for shifting said arms 13, and the elements of the device reposing upon platform 16 to their inoperative position shown in Fig. 1. When arms 13 are tilted toward bowl 10 by the action of handle 67 the shifting is against the tension of said spring 68.

Flexible tube 35, at its opposite end, connects with a valve box 69, which is in any suitable manner supported above the floor and rearwardly of bowl 10. Lever 70 is pivotally connected with one of said arms 13. The opposite end of said lever 70 connects with valve operating arm 71. City water pipe 72 connects to valve box 69. Normally the valve within box 69 remains shut. When

however handle 67 is shifted lever 70 also shifts for actuating and angularly shifting said valve operating arm 71 for opening the valve in the valve box 69. As long as the valve in said valve box 69 is open water flows from pipe 72 into tube 35 for actuating turbine wheel 32 as hereinabove described. Spring 68 is capable of retracting arms 13 into their inoperative position as well as of retracting lever 70 for actuating arm 71 for closing the valve in valve box 69 for cutting off the supply of water into casing 31 and for thereby rendering the device inoperative.

From the hereinabove description it will be seen that as handle 67 is depressed the cleansing device bodily shifts toward and above toilet bowl 10 against the tension of spring 68 at the same time assuming a lowered position due to the inclination of arms 13 for causing said wheel 54 to assume a level substantially corresponding to the level of the part of the user's body to be cleansed. The buttocks of the user guide the wheel 54 into the channel defined by the buttocks in order that wheel 54 may enter the said channel and assume a contactual position with the user's anal region. Springs 28 are capable of yielding for permitting arms 44 and members 50 to assume an angular position with relation to platform 16, as said wheel 54 enters the said channel. Said springs 28 maintain said wheel 54 in contact with the user's body to be cleansed. The shifting movement of the cleansing device on a vertical plane as permitted by the hinge arrangement of hinge arms 24 as they swing upon pintles 25. The degree of pressure of wheel 54 upon the user's body is regulated by adjusting the degree of tension of springs 28, which is accomplished by turning pintles 25 and their heads 27 into either direction for shifting the upper ends of springs 28 toward or away from plate 22. Recess 23 provides clearance for plate 22 past block 19 and pins 17 and 20 as the device shifts on a vertical plane upon hinges defined by said hinge arms 24 and pintles 25.

Although wheel 54 is centered with relation to bowl 10 facilitating said wheel to enter the said channel, nevertheless said wheel 54 is capable of shifting on a horizontal plane in either direction in order to accommodate itself to any particular off-center position of the user. This result is accomplished by virtue of the pivot defined by pin 17 upon which block 19 rotatably swings in either direction on a horizontal plane and against the tension of spring 21. Wheel 54 guided by the user's buttocks will cause arms 44 to shift in either direction, shifting the entire device upon its pivot pin 17 causing said spring 21 to yield as block 19 rotatably shifts. In this manner wheel 54 is caused to find the said channel to enter the same even though the channel may be at any given moment not in alinement with the longitudinal axis of wheel 54. As was hereinabove mentioned spring 21 seeking to assume its normal position will ultimately bring the entire device into its normal position with wheel 54 properly centered with relation to bowl 10.

In order to prevent contamination of the water supply by inadvertent backing or siphonage of the water which may remain in the device after usage, a check valve 90, or other means, may be connected in the line 72.

From the hereinabove description it will be seen that the cleansing device is capable of various adjustments to accommodate itself to any particular position of the user's body. By means

of handle 67 the device is bodily shifted towards and above bowl 67 and in a downward direction. By virtue of the hinge arrangement including arms 24, pintles 25 and springs 28 the device is capable of angularly shifting on a vertical plane and of causing wheel 54 to properly contact the user's body to be cleansed. Due to the action of pivot pin 17 and spring 21 the device is capable of adjusting itself on a horizontal plane for angularly shifting wheel 54 on the same plane.

As long as handle 67 is maintained in its downwardly shifted position the valve in valve box 69 is open permitting the flow of water into casing 31 for operating turbine wheel 32. The exhausting water flowing through tube 62 and gutter 64 acts upon wheel 54 for cleaning the same. Once handle 67 is released spring 68 acts upon one of arms 13 not only for bringing said arms 13 into their inoperative position but also for closing the valve in valve box 69 by virtue of automatic retraction of lever 70 and arm 71. Tube 35 being flexible permits the shifting of the assembly upon platform 16 with relation to said valve box 69.

25 The hub of wheel 54 may be made of hard rubber while the rim thereof may be made of softer rubber.

It is further observed that the upper edge of the cut-out in tube 62 defining said gutter 64 contacts with the periphery of the rim of wheel 54 and acts as a scraper for said rim (see Fig. 1), thereby removing any matter adhering to said rim.

35 Cotton roll 65 may be saturated with an anti-septic to act upon the rim of wheel 54. Tube 62, adjacent said roll 65, may be perforated for permitting water in small quantities to act upon roll 65 in order to keep it moist so that the anti-septic would be carried to the rim of said wheel 54.

While there is described herein a preferred embodiment of the present invention, it is nevertheless to be understood that minor changes may be made therein without departing from the spirit and scope of the invention as claimed.

45 What I claim as new is:

1. A toilet bowl device for cleansing posterior portion of the human body comprising a rotatable element, a supporting member upon which said rotatable element is supported, tensioning means coacting with said supporting member for maintaining the latter and said rotatable element in their normal inoperative position, a handle for manually bodily shifting said supporting member into a shifted operative position against the action of said tensioning means, a turbine, a valve box, a valve therewithin, a connecting tube between said turbine and said valve box, a connecting member between said valve and said supporting member, said valve being actuated by said connecting member on shifting of said handle for permitting flow of water into said turbine through said connecting tube, and connecting means between said turbine and said rotatable element for imparting a rotary movement to the latter when said rotatable member and said supporting member have been shifted into their operative position on shifting of said handle.

2. A toilet bowl device for cleansing posterior portion of the human body comprising a rotatable element, a supporting member upon which said rotatable element is supported, tensioning means coacting with said supporting member for maintaining the latter and said rotatable element in their normal inoperative position, a handle for

manually bodily shifting said supporting member into a shifted operative position against the action of said tensioning means, a turbine, a valve box, a valve therewithin, a connecting tube between said turbine and said valve box, a connecting member between said valve and said supporting member, said valve being actuated by said connecting member on shifting of said handle for permitting flow of water into said turbine through said connecting tube, connecting means between said turbine and said rotatable element for imparting a rotary movement to the latter when said rotatable member and said supporting member have been shifted into their operative position on shifting of said handle, and an exhaust tube connected by one of its ends with said turbine, the other end of said tube being positioned adjacent the rim of said rotatable element for ejecting the exhausted water from said turbine against the rim of said rotatable element.

3. A toilet bowl device for cleansing posterior portion of the human body comprising a base, a block supported upon said base, a casing, a rotatable element supported upon said casing, a motive element within said casing for imparting a rotary movement to said rotatable element, said rotatable element being normally supported outside of the perimeter of the toilet bowl, means for shifting said base toward the toilet bowl for bringing said element within the perimeter of the toilet bowl, a hinged connection between said casing and said block, and a tensioning means between said block and said casing, on operation of said second named means said tensioning means being capable of permitting yieldable shifting movement of said rotatable element upon said hinged connection for yieldably contacting the human body above the toilet bowl.

4. A toilet bowl device for cleansing posterior portion of the human body comprising a base, a vertical pivot pin rigidly supported upon said base, a block journaled by its center upon said pivot pin, a pair of pins one adjacent each end of said block and rigidly connecting therewith, a yielding element connecting all of said pins, a casing, a rotatable element supported upon said casing, said casing being connected with said block, a motive element within said casing for imparting a rotary movement to said rotatable element, said rotatable element being normally supported outside of the perimeter of the toilet bowl, and means for shifting said base, said cas-

ing and said rotatable element towards the toilet bowl for bringing said rotatable element within the perimeter of the toilet bowl, said block being capable of horizontal rotary shifting movement upon said pivot pin against the action of said yielding element for angularly shifting said casing and said rotatable element for conforming the position of the latter with relation to the human body upon a horizontal plane.

5. A toilet bowl device for cleansing posterior portion of the human body comprising a base, a block supported upon said base, a casing, a rotatable element supported upon said casing, a motive element for imparting a rotary movement to said rotatable element, said rotatable element being normally supported outside of the perimeter of the toilet bowl, a handle for shifting said base toward the toilet bowl for bringing said element within the perimeter of the toilet bowl, a hinged connection between said casing and said block, tensioning means between said block and said casing, on actuation of said handle said tensioning means being capable of permitting yieldable shifting movement of said rotatable element upon said hinged connection for yieldably contacting the human body above the toilet bowl, a conduit connecting a source of water with said motive element, a valve in said conduit, normally said valve being closed, and a connecting member between said valve and said handle, on actuation of said handle said connecting member being adapted to open said valve for permitting the flow of water through said conduit to said motive element for actuating the latter for imparting a rotary movement to said rotatable element, the exhausted water being adapted to flush said rotatable element.
